RETARDING MECHANISM

Harry Slavin, Detroit, Mich.

Application April 30, 1946, Serial No. 666,044

11 Claims. (Cl. 244—110)

1

This invention relates to retarding mechanisms and particularly to mechanism for retarding movement of vehicles, such as automobiles and aircraft.

An important object of this invention is to provide an improved retarding mechanism for slowing down and stopping vehicles in movement which is rugged and efficient in operation and which in inoperative position forms no obstruction to the passage of the vehicles. Another object of the invention is to provide an improved retarding mechanism including a barrier with which the vehicle engages, and novel means for permitting the barrier to move with the vehicle to lessen the full force of the impact and to bring the vehicle gradually to rest. A further object of this invention is to provide novel braking means for retarding the movement of the barrier when so engaged by a vehicle, which is automatically rendered ineffective when the barrier is moved in the opposite direction to its initial starting or operating position. A further object of the invention is to provide a novel readily installable unit comprising various operating elements for controlling and regulating the barrier in either direction of its movement, each element of which performs its particular function without interference from the other element of the unit.

More specifically, it is an important object of this invention to provide an improved frictional retarding device for slowing vehicles to rest which comprises a brake drum, brake shoes carried by a rotatable member and novel means for moving the brake shoes into engagement with the brake drum when rotation of the member occurs in one direction. Another important object of this invention is to provide a novel application of the retarding mechanism of this invention to the slowing down and ultimately stopping of aircraft making landings within limited areas.

In order to make the invention clearly understood, several embodiments of the invention are illustrated in the accompanying drawings for carrying out the invention into practical use. It is understood that these embodiments have, for the purpose of explanation, been made the subject of illustration, and that improvements in their useful application may be made which fall within the scope of this invention.

Various other objects, advantages and meritorious features will become more fully apparent from the following specification, appended claims and accompanying drawings wherein:

Figure 1 is a side elevation of the retarding mechanism in operative position.

mechanism of the present invention partly broken away in section to illustrate the interior construction.

Figure 2 is an end view of the retarding mechanism in operative position partly broken away in section.

Figure 3 is a side elevation of the control mechanism for regulating the movements of the barrier, partly broken away to show the interior construction.

Figure 4 is a cross sectional view of the control mechanism along line 4—4 of Fig. 3.

Figure 5 is a sectional view along line 5—5 of Fig. 1 showing the means for providing movement of the barrier.

Figure 6 is a detail sectional view along line 6—6 of Fig. 1 showing the means for projecting the barrier to initial operating position.

Figure 7 is a vertical sectional view along line 7—7 of Fig. 1 showing the barrier in operating position, and

Figure 8 is perspective view of an aircraft carrier showing the adaptation of this invention to the retarding of aircraft landing on the flight deck of the carrier.

Figure 9 is a detail view.

In the embodiments of the invention illustrated herein, the invention is applied to the retardation of moving road vehicles and aircraft. It is understood that where the term vehicle is used it is applicable to aircraft and other forms of wheeled conveyances. The retarding mechanism is mounted adjacent to a runway which in the case of a land vehicle may be a road or highway, and in the case of an airplane, a landing strip or deck. In either instance a barrier is employed which is engaged by the moving vehicle. When applied across the path of travel of a land vehicle the barrier may form relatively large obstruction, and when applied across an aircraft landing strip it may be a flexible member such as a cable.

Referring specifically to the drawings, the embodiment of the invention is shown in Figs. 1 and 2 as applied to a road or highway near an intersection such as another highway or a railroad crossing or before a bridge. The road is indicated at 10. It may slant upwardly at a slight incline as in Fig. 1, or extend to a level. When in operative position, there extends across the road a barrier member 12 which may be in the form of a heavy metal sheet as shown. Resilient snubbers 14 or other cushioning means may be mounted on the impact side of the barrier as shown. The opposite ends of the barrier are carried upon stanchions or posts 16—16 which are mounted

for travel parallel to the roadway. The barrier 12 may be directly connected to the posts 16-16 or as shown, flexibly connected thereto by the intermediary of short lengths of chain 18.

Each post 16 is guided for movement along either side of the road 10 in a direction generally parallel thereto. The guiding means for each post is in the form of a track upon which one or more rollers carried by the posts travel. As shown in Fig. 2, each track may be an I-bar 20 turned on its side and having part of its length embedded in a concrete support or abutment 22 which is also shaped to house the other parts of the mechanism. The end of the I-bar forms a top rail and a bottom rail. Two vertically spaced arms 24 and 26 fixed to the posts carry rollers 28 and 30 respectively which ride on the top and bottom rails.

For further support of the posts 16 and the barrier 12, each concrete abutment 22 may be provided with a longitudinal extending cavity or channel 32, one of which is shown at the right end of Fig. 2. The channel is generally L-shaped in cross section and the inner end of the I-bar 20 is arranged to be exposed in the upper portion of the channel. The lower arm 26 of the post is provided with an upwardly bent extension 34 carrying a roller 36 on its upper end. The latter as shown engages the inner end of the bar 20 and rolls therealong as the barrier moves.

The tracks along which the posts 16-16 are guided extend on the same substantially horizontal level for the major portions of their respective lengths. In the illustrated embodiment of the invention in Figs. 1 and 2, this level is slightly above the surface of the roadway. The concrete abutments 22 likewise are shown rising above the level of the highway. By providing longer posts 16 it is possible to lower the level of the tracks and the concrete support so that the top portion of the latter is substantially flush with the surface of the road.

The ends of the tracks 20 are correspondingly curved downwardly as indicated at 38 at the right of Fig. 1 and 40 at the left of Fig. 1. The two rollers 28 and 30 of the posts follow the downward curvature of these rails and as evident will swing the posts to a horizontal position at either end of the track. The barrier 12 carried by the posts will likewise take a horizontal position when the posts are moved to either extremity of the tracks. The short lengths of chain 18 will allow the barrier to lie flat upon the road surface regardless of whether the posts lie slightly above or below the road level in their horizontal positions. In these two positions the barrier forms no obstruction and vehicles may pass thereover without difficulty.

The right hand end of Fig. 1 may be considered as the initial operating position of the barrier. Normally it will lie inoperatively upon the roadway in the plane of the post 16 shown in full lines. To raise the barrier to its initial operating position, there is associated with each track an electric motor 42 (Fig. 7). Other power or manual control means may be provided in lieu thereof. The motor 42 is connected to a cable winding drum 44 having a cable 46 attached to a horizontal bar 48. As shown at the right of Fig. 1, the bar 48 is guided to an arcuate slot 50 formed in a separate body 52 embedded in the abutment 22 and conforming to the downward curvature of the rail section 38. The outer end of this bar extends toward the road a sufficient distance to engage the rear side of the post with

which it is associated. The inner end of the bar within the slot 50 is provided with one or more rollers 54 for frictionless bearing on the base 56 of the slot. At the upper end of the slot 50 a stop in the form of a member 58 is provided for limiting the movement of the bar 48 when it has reached the upper end of the slot. It is evident that upon winding in the cable 46 on the drum 44, the bar 48 will be raised in the slot and carry the post with which it engages to an upright position adjacent the downwardly curved end section 38 of the track. This is the initial operating position of the posts and barrier.

A vehicle proceeding along the runway and entering the area between the tracks will strike the barrier 12 and by virtue of the tracks or rails upon which the posts are guided will carry the barrier therewith. To gradually reduce the movement of the vehicle and bring it to rest if the speed of the vehicle is not too high, a compact unitary retarding mechanism is associated with each track 20. Each of these mechanisms is located preferably in a concealed protected position below the level of the road and under track with which it is associated. Each retarding mechanism is connected to the barrier through the means of a flexible connection in the form of a cable 60 partially wound on the cable winding drum 62. On one side of the drum 62 is a control device for returning the barrier to either its initial operating position or its depressed inoperative position. This control device is preferably a power operated mechanism in the form of an electric motor 64 having its drive shaft 66 connected directly to the drum 62, but may for certain installations be a manually controlled device. On the other side of the winding drum 62 is a brake device operable to retard the rotation of the winding drum when the cable thereof is unwound therefrom but is incapable of effecting the rotation of the drum when the drum is rotated to wind the cable thereabout.

Referring specifically to Figs. 3 and 4, the retarding device comprises a fixed brake drum 68 having a rotatable member 70 concentrically mounted therein. The member 70 is fixed to a shaft 72 journaled in suitable bearings provided in the side wall supports 74 of the brake drum. The shaft 72 extends toward the cable winding drum and is preferably mounted in axial alignment therewith but may be disposed offset thereto if desired. Operatively coupling the rotatable member to the cable winding drum is a one-way drive mechanism operating through gearing which rotates the member 70 at a faster rate than the cable winding drum.

The one-way drive mechanism may be any suitable form of device of this character and is herein shown as a helical spring member 76 interposed between an outer sleeve 78 and limb 80 forming an extension of the cable winding drum. One end of the spring is adapted to be engaged by a radial projection 82 on the shaft 80 and the other end is adapted to be engaged by a pin 84 forming a stop against which the end of the spring member abuts. The relation of the projection and the stop is such that when the cable winding drum rotates in the direction to unwind the cable therefrom the end of the spring member is engaged by the projection 82 and expanded thereby into frictional engagement with the inner surface of the sleeve 78. So long as the sleeve is rotating slower than the hub the spring member will expand into engagement therewith and frictionally urge it to rotate at the same speed. However, if the cable winding drum

is rotated in the opposite direction to wind the cable therearound, the projection 82 and the stop pin 84 will escape past the ends of the spring member and the rotatable member 70 within the brake drum is freed from control by the cable winding drum.

As previously mentioned the rotatable member is driven at a faster rate than the cable winding drum. This is accomplished by suitable reduction gearing between the sleeve 78 and the shaft 72 of the rotatable member. As shown in Fig. 3 a shaft 86 is arranged parallel spaced relation to the shaft 72 and supported on the one hand by the adjacent side wall 74 of the brake drum and on the other hand by a side wall support of the cable winding drum 62. A pair of gears 88 and 90 of unequal sizes are freely rotatable on shaft 86. These gears mesh with gears 92 and 94 respectively, the former carried by the sleeve 78 and the latter being keyed to the shaft 72 for joint rotation therewith. For support and proper alignment of the parts, the shaft 72 is provided with a reduced end section which enters the hub 80. The latter as well as the sleeve 78 and the gear 92 carried thereby are freely rotatable with respect to the shaft 72 and its extension. It is evident that the gearing will drive the rotatable member 70 at a faster rate of speed than the cable winding drum.

Novel means is provided which is automatically operable upon rotation of the member 70 to resist such rotation and through the gearing connection to the cable winding drum retard the rotation of the latter. This novel means is relatively ineffective when the member is rotated slowly but increases in effectiveness the faster the member is rotated. This means comprises one or more internal expanding brake shoes carried by the member 70. Three such brake shoes are shown in the illustrated embodiment of the invention at 96. Each brake shoe is supported for radial movement by means of two sets of roller bearings 98 and 100 which bear on the transverse and longitudinal surfaces of the member. In Fig. 3 one set of rollers 98 is shown on the opposite ends of the brake shoes. In Fig. 4 the second set of rollers 100 is shown bearing on V-shaped supports 102 forming part of the member 70. All the brake shoes are yieldingly urged to a retracted position out of engagement with the brake drum by springs 106.

Mounted axially on the shaft 72 and rotatable therewith is a longitudinally slidable member 108 having a conical portion 110 and a reduced end section 112 entering and slidably fitting a passage in the shaft 72 in which a coiled spring 114 under tension is located. The latter yieldingly urges the member 108 outwardly of the shaft. On the outer projecting end of the member 108 is a centrifugal governor device including balls 116 and pivoted arms 118. As will be understood the balls 116 of the governor will fly out upon rotation and such action will bring down the arms together and urge the member 108 inwardly against the resistance of the spring 114. Mounted in radial openings in the shaft 72 are a plurality of balls 120, one corresponding to each brake shoe. Each brake shoe is provided with a concave seat for receiving its respective ball, but normally the balls lie loosely therein. The balls 116 are located at substantially the juncture of the conical portion 110 to the reduced end section 112, but when the member 108 is forced inwardly by the governor, the conical portion will push the balls 120 outwardly into their respective 75

seats in the brake shoes and further pressure will radially expand the brake shoes into engagement with the brake drum. The faster the member 70 is rotated the more force will be exerted by the governor to press the shoes into engagement with the brake drum.

The retarding mechanism hereinabove described is especially adaptable for slowing down and bringing to a rest aircraft making landings within restricted areas. In Figure 8 the invention is shown applied to an aircraft carrier represented at 122 having a flight deck 124. Extending across the deck are a plurality of longitudinally spaced cables 126 corresponding in function to the barrier 12 previously described. These cables are adapted to engage suitable hook-like means carried by the airplane making the landing on the deck to arrest its movement after it has landed.

20 The opposite ends of the cables are secured to posts 128 on opposite sides of the flight deck which are mounted for longitudinal movement along the deck similarly to posts 16-16 previously described. A retarding mechanism of the character shown in Figures 3 and 4 is operatively coupled with the posts 128 for gradually bringing the posts and cables to rest after engagement by an aircraft landing on the deck. In order to interconnect two or more transverse cables with 25 one another so that their retarding effect is added together, longitudinally extending cables 130 may be used. The last mentioned cables are preferably detachably connected at their opposite ends to the transverse cables 126 by snap-hooks 132 of the character illustrated in Figure 9. By this provision the cables 130 are capable of optional use and may be quickly connected to or disconnected from the transverse cables.

30 The posts 128 are shown as extending upwardly around the edges of the flight deck 124. The lower ends of the posts may be bent inwardly for sliding engagement with a track or rail structure of the type illustrated in Figures 1 and 2. However, the posts may be guided by rails under the deck and extend upwardly through longitudinal slots opening out on the deck.

35 It may be desirable in cold weather areas to use heating devices for melting ice and keeping 40 the parts in a freely operable condition. Electric heating coils, for example, may be installed in the barrier and adjacent to the retarding mechanism therefor. Ice melting chemical compounds may also be used if desired.

45 The same barrier 126 guided along tracks may be also utilized as a means for accelerating the movement of an airplane when picking up speed for a take-off from an airfield runway or deck of a ship, the motivating force being derived 50 either from the winding up of the cables about the drums, or from the exertion of a force upon the barrier by motorized carriers running along the tracks of the installation. A device remote 55 from the barrier and the track may be utilized to control the operation of the barrier and to vary its speed.

What I claim is:

1. In combination with a runway over which a vehicle is adapted to travel, a pair of posts each located on a side of the runway opposite to the other and mounted for bodily translational movement in upright position parallel to the runway, a barrier adapted to be supported by said pair of posts over the runway for engagement by a vehicle traveling therealong, and

means for yieldingly resisting movement of the posts in one direction of their movement.

2. In combination with a runway over which a vehicle is adapted to travel, a pair of posts each located on one side of the runway opposite to the other, a barrier element connected to the posts and extending transversely across the runway, means guiding said posts for bodily translational travel in a substantially vertical position along separate paths parallel to the runway, means for causing each post adjacent a corresponding end of their respective paths of travel to move from said substantially vertical position to an inoperative substantially horizontal position, means for imposing a yielding resistance to the travel of the posts in one direction from an initial starting position, and means for returning the posts to their initial starting position.

3. In combination with a runway over which vehicles are adapted to travel, a pair of members each located on one side of the runway opposite to the other, a barrier element extending transversely across the runway and having its opposite ends connected to said pair of members, means guiding said members for bodily translational movement along separate paths parallel to the runway and at a level above the level of the runway so as to support the barrier element in elevated position above the runway for engagement by a vehicle traveling therealong, means adjacent a corresponding end of the path of travel of each member for causing the member to move downwardly toward the level of the runway and thereby carry the barrier element to an inoperative position substantially flush with the level of the runway, and means for imposing a yielding resistance to the movement of the members in one direction of their bodily translational movement.

4. In combination with a runway over which vehicles are adapted to travel, a pair of members each located on one side of the runway opposite to the other, a barrier element extending transversely across the runway and having its opposite ends connected to said pair of members, means guiding said members for bodily translational movement along separate paths parallel to the runway and at a level above the level of the runway so as to support the barrier element in elevated position above the runway for engagement by a vehicle traveling therealong, means adjacent a corresponding end of the path of travel of each member for causing the member to move downwardly toward the level of the runway and thereby carry the barrier element to an inoperative position substantially flush with the level of the runway, means for imposing a yielding resistance to the movement of the members in one direction of their elevated bodily translational movement from an initial starting position which resistance automatically increases proportionate to the speed of movement of the members, said last means acting only in said direction of movement and being automatically inoperative upon return movement of the members to their initial starting position, and means for returning the members to their initial starting position.

5. In combination with a runway over which vehicles are adapted to travel, a track extending alongside of said runway and provided at one end thereof with a downwardly curved section, a barrier adapted to be erected across the runway, means guiding said barrier along said

track for the major portion of the length thereof in operation projecting position for engagement by a vehicle, said guiding means following the downward curvature of said end section to carry the barrier therewith to an inoperative position substantially flush with the surface of the runway, a cable winding drum having a cable thereon connected to said barrier, power means operatively coupled to said winding drum to wind in the cable, a rotatable member, a one-way drive mechanism coupling said member to said winding drum and operative when the cable is unwound from the drum to rotate said member, but when the cable is wound upon the drum to release the member from rotation, and means for frictionally retarding rotation of said member.

6. In combination with a runway over which a vehicle or the like is adapted to travel, a track extending alongside of the runway and provided at one end with a downwardly curved section, a barrier adapted to be disposed in the path of travel of a vehicle on the runway, means guiding said barrier along said track and for the major portion of the track length supporting said barrier in operative position projected above the surface of the runway for engagement by a vehicle, said guiding means adapted to follow the downward curvature of said track and carry the barrier therewith to an inoperative position substantially flush with the runway, means for raising said barrier to an initial projecting operating position adjacent to said end section of the track, a cable winding drum having a cable thereon attached to said barrier and adapted upon movement of the barrier along said track away from said end section to unwind from the drum, power means on one side of the drum operatively connected thereto and adapted to rewind the cable thereon and return the barrier to its inoperative position, and retarding mechanism on the other side of the drum, and means operatively connecting said retarding mechanism to the cable winding drum when the cable is unwound therefrom.

7. In combination with a runway over which a vehicle or the like is adapted to travel, a track extending alongside side of said runway having the major portion of its length on one level and the opposite ends thereof provided with downwardly curved sections, a barrier adapted to be disposed in the path of travel of a vehicle on the runway and means guiding said barrier for movement along said track and for said major portion of the length of the track supporting the barrier in operative projected position above the runway for engagement by a vehicle, said guiding means adapted to follow the downward curvature of said end sections of the track and carry the barrier therewith to inoperative positions at either end of the track substantially flush with the surface of the runway.

8. The invention described in claim 7 characterized by the provision at the opposite ends of the track for yieldingly cushioning the downward movement of the barrier as it approaches its inoperative flush position with the runway.

9. In combination with a runway over which a vehicle or the like is adapted to travel, a track extending alongside of said runway having the major portion of its length on one level and provided with a downwardly curved section at one end thereof, a barrier adapted to be disposed in the path of travel of a vehicle on the runway, means guiding said barrier for movement along

said track and for said major portion of the length of the track supporting said barrier in operative projected position above the runway for engagement by a vehicle, said guiding means adapted to follow the downward curvature of said end section of the track and carry the barrier therewith to an inoperative position at said end of the track substantially flush with the surface of the runway, a rotatable cable winding drum having a cable thereon connected to said barrier, means for raising said barrier and the guiding means associated therewith relatively slowly from said inoperative position to an initial operative position adjacent to said end of the track, power means operatively coupled to said winding drum and adapted to rotate the drum and wind in the cable to return the barrier from whatever position it may have along the track to said inoperative flush position, a brake drum, a rotatable member concentrically mounted within the brake drum carrying internally expandible brake shoes, a one-way clutch device operatively coupling said cable winding drum to said rotatable member and rotating the latter only when the cable is unwound from the drum, and means for automatically expanding said brake shoes into engagement with said brake drum when said member is rotated at a relatively high speed.

10. In combination with an aircraft landing strip, a pair of members each mounted on one side of the landing strip opposite to the other, a barrier element extending transversely across the landing strip and having its opposite ends connected to said pair of members, track means for guiding each of said members for bodily translational movement along a path parallel to the landing strip and at a level elevated above the level of the landing strip so as to support the barrier element in raised position for engagement by an aircraft making a landing on the strip, means adjacent a corresponding end of the path of travel of each member for causing the member to move downwardly toward the level of the landing strip and thereby carry the barrier element to an inoperative position substantially flush with the level of the landing strip, and means for imposing a yielding resistance to the

movement of the members in one direction of their bodily translational movement.

- 5 11. In combination with the flight deck of an aircraft carrier, a pair of tracks extending along the opposite sides of the flight deck generally parallel to the direction of travel of aircraft making landings on the flight deck, a member guided in each track and capable of bodily translational movement therealong from one end of the track to the other end thereof, a barrier element extending transversely across the flight deck and having its opposite ends connected to said members, said tracks so constructed that for the major portion of the translational movement 10 the members are movable at a level above the level of the flight deck so as to support the barrier element in raised position above the flight deck but at the opposite ends of the tracks the members are caused to be moved downwardly toward 15 the track and thereby carry the barrier element from a raised operative position to an inoperative position substantially flush with the flight deck, and means for imposing a yielding resistance to the movement of the members in one direction 20 of their bodily movement from an initial starting position adjacent to one end of the tracks, said last means automatically increasing the resistance directly proportional to the increase in speed of movement of the members along their 25 respective tracks, and means for returning the members to their initial starting position.
